(57) **CLAIM**

The ornamental design for a wrist watch with earphone/microphone, as shown and described.

DESCRIPTION

FIG. 1 is a front elevational view of a wrist watch with earphone/microphone in accordance with my new design;

FIG. 2 is an enlarged front elevational view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a top plan view thereof;

FIG. 8 is a right front perspective view thereof;

FIG. 9 is a left front perspective view thereof;

FIG. 10 is a left front perspective view of the wrist watch of FIG. 1 with the strap buckled;

FIG. 11 is a left front perspective view of the wrist watch with the main unit removed from the strap; and,

FIG. 12 is a fragmentary right side perspective view of the wrist watch with earphone/microphone shown in an exploded condition with portions of the strap omitted for ease of illustration.

The views are shown on different scales. The strap is shown in different positions in the various views. The broken lines showing the time on the watch display are for illustrative purposes only and form no part of the claimed design.
